UNITED STATES PATENT OFFICE.

HOWARD C. DAVIS, OF ELIZABETH, NEW JERSEY, ASSIGNOR TO AMERICAN MARINE EQUIPMENT CORPORATION, A CORPORATION OF DELAWARE.

EVAPORATOR, FEED-WATER HEATER, AND THE LIKE.

Application filed January 7, 1920. Serial No. 349,985.

To all whom it may concern:

Be it known that I, HOWARD C. DAVIS, a citizen of the United States, residing at Elizabeth, in the county of Union and State 5 of New Jersey, have invented certain new and useful Improvements in Evaporators, Feed-Water Heaters, and the like, of which the following is a full, clear, and exact description.

10 My invention relates to evaporators, feed water heaters and the like, one of the objects of the invention being to provide an improved construction of, and method of mounting, the heating coils whereby the 15 coils are made interchangeable and reversible, and are rendered easily accessible for removal or repairs, without disturbance of the other coils, and whereby they may be connected to the feeder and discharge pipes 20 in such a manner that any one or more of the coils may be removed without affecting the operation of the device with the remaining coils.

A further object of the invention is to 25 provide a heating coil which has a maximum of heating surface in a minimum of space, is free from sharp turns and has both of its terminals at its periphery.

A further object is to provide means for 30 preventing vibration, sagging and consequent chafing of the coils one on another, when assembled.

A further object is to provide a multiple 35 coil unit in which the temperature in each coil can be separately regulated as desired under a constant steam pressure in the supply pipe.

A further object is to provide a device of 40 this kind which, when used as an evaporator, will keep the formation of scale down to a minimum.

Other objects and advantages will be apparent from the following description and the novel features of my invention will be 45 particularly pointed out in the claims.

In the drawings:

Fig. 1 is a front elevation of an evaporator embodying my invention;

Fig. 2 is a vertical central sectional view 50 of the same;

Fig. 3 is an elevation on an enlarged scale of the evaporator shell or casing with the closure plate or cover removed;

Fig. 4 is a top plan view of the evaporator with the vapor dome removed; 55

Fig. 5 is a horizontal section of the same;

Fig. 6 is a detail sectional view of the coupling between one of the headers and a terminal of one of the coils, and

Fig. 7 is a partial sectional elevation 60 through one of the headers and a few of the nipples.

The main shell or casing 1 may be of any suitable shape. It has an opening in its side wall, for access to the interior, which is normally covered by a door or closure 2 removably attached thereto, as by bolts 3. Upon opposite sides of the casing 1, adjacent the side edges of the closure, and extending parallel therewith for substantially the 70

length of the casing, are headers or conduits 4 and 5, which are preferably cast integral with the casing. The casing is divided into a plurality of compartments or chambers by a series of partitions or baffle plates 6 which 75

extend forwardly from the rear wall and alternately from opposite sides of the casing nearly across the interior thereof. A series of ribs 7 on the inner face of the door or closure 2 are in line with and form an extension of the baffle plates 6 and extend the 80

chambers or compartments entirely to the front of the casing. Due to the fact that the baffle plates 6 extend from each side alternately nearly across the casing, each 85

chamber or compartment communicates with the adjoining chambers at opposite ends. That is, the passages between the chambers or compartments are not in alignment but 90

are arranged in staggered relation, thereby forming a tortuous ascending passage 95 through the casing.

Disposed within each chamber is a heating unit 8 which comprises a double coil of pec- 100

uliar construction. It is made up of two sections, the convolutions of each section lying in the same plane with each other but in a plane parallel to those of the adjacent section. In forming the double coil the pipe

from which the same is produced is bent spirally inwardly from its periphery to form one section, is then bent downwardly or laterally from a point adjacent the center of the section to the plane of the adjoining section, and is then bent spirally outwardly in the 105

same direction to the periphery to form the

second section. The terminals 9 and 10 of the coil are thus located at the periphery thereof and when the coil is in place in the casing 1 said terminals lie at points adjacent the opposite side edges of the door or closure 2. All sharp bends in the coil are avoided by this construction, and the coils are rendered reversible and interchangeable. Both sections of the coils are substantially parallel with the baffle or partition plates 6. One terminal 9 of each coil is removably connected to the header 4 by any suitable coupling 11 and the other terminal 10 is similarly connected to the other header 5. The coupling 11 may conveniently comprise a nipple 12 threaded at one end into an opening 13 in the header and communicating with the passage therein, and having its other end threaded to receive a threaded cap or nut 14 through the end of which the coil terminal passes. The end of the terminal is flared and held against the beveled end of the nipple by a ferrule 15 which is in turn pressed toward the end of the nipple 12 by the end wall of the nut 14. This provides a suitable joint which permits of quick and easy attachment or detachment, between the coil terminal and header, by the application of the nut to or its removal from the nipple. The nuts 14 are easily accessible from the front of the casing when the door or closure 2 is removed so that each heating unit or coil can be removed or inserted without disturbance of or hindrance by the other coils or units.

The nipples 12 which connect the various coil terminals 10 to the header 5 may have openings which vary in size, so that the amount of steam admitted to any one unit or coil is dependent upon the size of the opening in the particular nipple used. The nipples may be arranged in any desired order with respect to the size of the passages therein, along the length of the header, but I preferably arrange them with openings or passages varying from a minimum at the top to a maximum at the bottom of the header. Steam is supplied to header 5 through an inlet 16 and passes therefrom into the various coils or heating units. A steam trap (not shown) is connected to the outlet end 17 of the header 4. When a solution such as sea water, is evaporated, the solution becomes more dense, the denser portion settles to the bottom, and steam at a higher temperature is thus necessary to evaporate the liquid at the bottom of the casing than is necessary for the less dense liquid in the upper portion of the casing. The temperature of the steam passing through the coils 8 varies with its pressure, and greater expansion takes place in the steam which passes into the coils through the smaller openings in the stems 12 than in the coils supplied through the larger openings. Thus

the temperature or effective heat imparted to the coils 8 by the steam therein varies progressively from a minimum at the top to a maximum at the bottom so that the body of water or liquid being evaporated in the casing is kept at a temperature substantially at the evaporation point throughout. The passages through the nipples 12 from the feeding header 5 may be uniform in size if desired but I have found the varying sizes specified to be a more efficient and preferable construction. By varying the nipples 12 according to the size of the passages therethrough, the heat imparted to each coil or unit can be selectively varied as desired. 75 80

When certain liquids such as sea water are evaporated, a scale tends to collect or form on the heating surfaces and on the inner walls of the casing. The formation of this scale is greatest at some distance from the point where the fresh liquid is supplied to the casing. To overcome the same, I propose to supply the feed water or liquid alternately at different points in the casing, so that the fresh liquid entering the casing at 85 any point will tend to dissolve off any scale which may have formed while the liquid was being supplied at another point in the casing. The liquid is drawn or blown off at intervals when the density exceeds a certain 90 amount and fresh liquid supplied, or the blowoff may be a gradual one. This removal of the denser liquid carries off the scale-forming substances contained therein. In the construction illustrated, I supply the 95 liquid to be evaporated through a pipe 18 to a vertical pipe 19 extending along the casing and connecting with a plurality of the chambers formed by the baffle or partition plates 6. The connections shown are with 100 the top and bottom chambers. In the vertical pipe 19 I provide a pair of valves 20 and 21, to determine through which chamber in the casing the feeding or fresh liquid is to be supplied. Leading from the lowermost 105 chamber is a blow off outlet 22 which may be left partly open, or be opened to greater extents at intervals to carry off the liquid with the high percentage of scale forming substances therein. I prefer to close valve 21 and open valve 20 for a short time and then close valve 20 and open valve 21 to supply the fresh liquid alternately to the bottom and top chambers for the purpose described. 110 115

When rapid ebullition of a liquid occurs a considerable amount of liquid is entrained in the vapor and carried along with it. Unless some means of removing this entrained liquid be provided the liquid of condensation will not be a pure distillate. I therefore 120 provide a steam or vapor dome 23 on top of the evaporator casing the same having a curved conduit 24 therein for deflecting the vapor or steam against the walls of the dome a short distance above the bottom thereof 125 130

and permitting the entrained liquid to settle out and be collected at the bottom of the dome, from which it is conducted by a pipe or conduit 25 to one of the chambers below the liquid level in the casing. At the upper discharge end of the dome is a conduit 26 which is curved oppositely to conduit 24 so that a somewhat tortuous path through the dome must be traversed by the vapor or steam before it passes off to the condenser (not shown). The steam or vapor dome being of larger volume, or area, than the passages 24 and 26 will cause a slower movement of the vapor therethrough, so that any entrained liquid may settle to the bottom and be conducted back to the evaporator casing, while the oppositely curved conduit ends (24 and 26) will prevent the direct passage of the vapor and entrained liquid. A suitable water or liquid gauge 27 is connected between the dome and the lower portion of the evaporator by connections 28 and 29, so that the level of the liquid in the evaporator casing will be indicated at all times.

Inasmuch as the evaporator will be commonly used adjacent running machinery, it will be subject to vibrations therefrom. In order to prevent vibration and consequent chafing of one portion of a coil 8 on another portion, as well as to prevent sagging or deformation of the coil due to its weight, I propose to provide a flat strap 30 along each of the outside faces of the coil unit and another strap 31 between the two sections of each coil, and clamp these straps together by any suitable means such as bolts 32, to hold the coils against relative movement.

In use, the heating steam is supplied to the header 5 through a connection 16 from which it passes to all the coils, and the water of condensation passes out through the header 4 and connection 17 to a steam trap (not shown). The liquid to be evaporated is supplied through pipe 18 to the vertical branch pipe 19. By operation of the valves 20 and 21, the liquid may be alternately supplied to the top and bottom chambers to keep the scale formation to a minimum. When the density of the liquid in the casing rises beyond a certain amount, the liquid is blown off through outlet 22 at the bottom of the casing in order to carry off the concentrated solution containing a high percentage of scale forming substances. If desired, of course, the blowoff may be a gradual, continuous one instead of an intermittent complete one. The liquid as it is evaporated passes upwardly through the tortuous passage from one chamber or compartment to another until it finally passes out through the dome of the condenser. The passage of the vapor through the various chambers, as described, increases the efficiency and effectiveness of the evaporator.

It will be observed that in a construction jacent each side of and parallel with the

according to my invention, the coils 8 are reversible, and the terminals 9 and 10 are at the periphery of the coil where they are readily accessible when the door or closure 2 is removed, so that the coil units may be separately removed or repaired without disturbance of, or hindrance from, the other coils. By removing a coil and supplying blank caps to the stems where the removed coil was originally connected the function or use of the evaporator may be continued with only a slight reduction in capacity until a new coil can be secured or the old one repaired. This is of especial importance when the evaporator is used on ships because in such cases new or repair parts are not always quickly available.

While I have described my invention with reference to its use as an evaporator it is obviously not confined to this use. In fact I propose to employ it in the construction of feed water heaters and condensers, and for the heating and cooling of liquids generally. The coils 8 have been described as being designed to receive the heating medium, steam, with the liquid to be treated surrounding said coils, but it is obvious that either a heating or a cooling medium may be used in the coils, and that a heating or cooling medium may be used on the outside of the coils with the liquid to be treated passing through the coils.

I claim:

1. In an apparatus of the character described a casing, said casing having a removable side wall acting as a closure therefor, a header disposed along the casing adjacent each side of and parallel with the closure, a plurality of coil units within the casing each extending between and connecting said headers, baffle plates disposed between adjacent coil units and extending alternately from opposite sides of the casing nearly across the same, whereby the passages between the different chambers formed by the baffle plates are staggered with relation to one another, and plates carried by the closure abutting against the baffle plates of the casing to complete the chambers entirely to the closure.

2. In an apparatus of the character described, a casing, said casing having a removable side wall acting as a closure therefor, a header disposed along the casing adjacent each side of and parallel with the closure, a plurality of substantially parallel coil units connecting said headers the connections between a plurality of the units and one of said headers having openings of different sizes.

3. In an apparatus of the character described, a casing, said casing having a removable side wall acting as a closure therefor, a header disposed along the casing adjacent each side of and parallel with the

closure, a plurality of substantially parallel coil units connecting said headers, the connections between a plurality of the units and one of said headers having openings progressively varying in size.

4. In an apparatus of the character described a casing, said casing having a removable side wall acting as a closure therefor, a plurality of plates extending across the 10 interior of said casing, ribs carried by the closure and co-operating with said partitions to form a series of communicating chambers, heating units in said chambers, and means for at will supplying a fluid to 15 said casing through any of a plurality of said chambers.

5. In an apparatus of the character described, a casing, a plurality of heating units in said casing, a plurality of baffle plates arranged in said casing between certain of the 20 units, and means for supplying a fluid to be heated alternately to different portions of the casing.

6. In an apparatus of the character described a casing, said casing having a removable side wall acting as a closure therefor, a plurality of plates extending across the 25 interior of said casing, ribs carried by

the closure and co-operating with said partitions to form a series of communicating 30 chambers, heating units in said chambers, and means for supplying a fluid to one of said chambers.

7. In an apparatus of the character described, a casing, a closure therefor, a plurality of spaced plates within the casing and supported by the walls thereof, plates carried by the closure and co-operating with the other plates to form a plurality of chambers within said casing, coil units within 40 said chambers, connections leading from the exterior of the casing to said coil units and connections leading to a plurality of said chambers.

8. In an apparatus of the character described, a casing having a chamber therein, coils passing through the chamber for heating its contents, and a plurality of connections opening into said casing at separated points for supplying a fluid to be 45 heated to said casing at more than one point.

In witness whereof, I hereunto subscribe my signature.

HOWARD C. DAVIS.
